FIG.3

FIG.4

FIG. 5

FIG. 6

FIG. 7

FIG. 8

FIG. 9

FIG. 1 is a front elevational view of a jar embodying my new design;

FIG. 2 is a side elevational view;

FIG. 3 is a top plan view;

FIG. 4 is a bottom view;

FIG. 5 is a sectional view taken along line 5—5 of FIG. 1;

FIG. 6 is a sectional view taken along line 6—6 of FIG. 2;

FIG. 7 is a sectional view taken along line 7—7 of FIG. 1;

FIG. 8 is a view similar to FIG. 5 but showing another embodiment of my new design wherein the only changes from the first embodiment are in the flattened top and bottom surfaces as shown; and

FIG. 9 is a view similar to FIG. 6 but showing the second embodiment.

I claim:

The ornamental design for a jar, as shown and described.
